UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

WINDOW-FRAME.

1,240,735.

Specification of Letters Patent. Patented Sept. 18, 1917.

Application filed September 21, 1915. Serial No. 51,843.

To all whom it may concern:

Be it known that I, GEORGE B. KOHLER, a citizen of the United States, residing in Philadelphia, Pennsylvania, have invented 5 certain Improvements in Window-Frames, of which the following is a specification.

My invention relates to certain improvements in window frames of the type in which the sash is allowed to pass through 10 an opening in the sill when it is desired to open the window.

The invention is particularly adapted for use in connection with passenger cars, but it will be understood that it can be used 15 in other window frames.

The object of my invention is to provide means for closing the opening when the sash is in the raised position and also, in some instances, to close the opening when 20 the sash has been lowered in the space below the sill.

This object I attain in the following manner, reference being had to the accompanying drawings, in which:—

25 Fig. 1, is a sectional perspective view illustrating my invention;

Fig. 2, is a sectional elevation, showing the sash raised and the opening closed;

Fig. 3, is a view of the sash partly lowered into the opening and the closing device 30 pushed back clear of the sash;

Fig. 4, is a sectional view, showing the sash lowered to the open position, but not fully into the opening, the sash projecting 35 sufficiently above the sill to allow it to be grasped so that it can be raised, when necessary;

Fig. 5, is a sectional view, showing the sash lowered entirely below the sill and the 40 opening closed; and

Fig. 6, is a perspective view of the closing device.

Referring to the drawings, 1 is the outside panel of the car, made in any suitable manner, and 2 is the inside panel. These panels are preferably made of sheet metal pressed into shape and reinforced in any manner desired. 3, 3 are the metallic posts which separate the car window openings, and 50 grooves 4 are formed in these posts and act as guides for the sash 5, which may be of any ordinary construction and may be either of wood or metal. 6 is the inner sill which, in the present instance, forms a continua-

tion of the inside panel 2, being bent at its 55 outer edge to form a downwardly extending flange 7. 8 is the outer sill forming a continuation of the outer panel 1 of the car body in the present instance, and this sill has a vertical flange 9. The two flanges 7 60 and 9 are spaced a sufficient distance apart to allow for the passage of the sash 5.

It has been the practice in making a window frame, in which the sash is lowered into a space below the sill, to leave the entrance 65 to this space entirely open. This not only allows the rain to beat in through this opening, but also allows a draft, which is objectionable in this type of car, and the main feature of applicant's invention is to 70 provide a device for closing this opening and also to provide means for closing the opening when the window is entirely within the space below the sill. 75

10 is the closing device consisting of a plate pivoted to the frame of the car at 11. In the present instance, this plate 10 has a vertical portion 12 and a shaped flange 13; the portion 14 of the flange being located under the inner sill, the portion 15 bearing against the flange 7 when the device is in the closed position, and the portion 16 forming a continuation of the two sills and also forming a cover for the opening 85 through which the sash extends.

17, 18 are blocks, in the present instance secured to each end of the closing device 10 and having pins which form the pivots 11. At the center of the flange 13 is a stop 90 18, which is shaped to engage the flanged end of the inner sill 6, as clearly shown in Fig. 3, when the closing device is moved to its extreme open position, but the form of this stop may be modified without departing from the essential features of the invention and it may be located at each end of the closing device instead of at the center, if found desirable. I preferably notch the posts at 19, Fig. 3, so as to allow the 100 ends of the portions 16 of the closing device to extend into the posts, and this forms a stop for the closing device when in the closed position, as illustrated in Figs. 2 and 5.

The sash may be raised and lowered by 105 hand, or may be manipulated by mechanical means without departing from the spirit of the invention. In the present instance,

while the closing device is moved to the closed position by gravity, a spring may be used, if found desirable.

When the sash is raised it is lifted above the outer sill sufficiently to allow the closing device to move forward, so as to close the opening in the sill, then it is allowed to drop onto the closing device. When in this position, the construction is such that it will 10 turn water and will form a comparatively tight joint.

When it is desired to open the window the sash is raised and the closing device is drawn back so as to expose the opening, 15 after which the sash is lowered into the opening, either into the position illustrated in Fig. 4, with the portion of the sash extending above the sill, or entirely below the sill, as in Fig. 5, in which position the device moves over the sash and closes the opening.

I claim:

1. The combination of a window frame having guides and having an inner and an outer sill spaced apart to form a passage, 25 the inner sill having a depending flange forming a stop, the outer sill having a ver-

tical flange at the passage; a pivoted closing device pivoted to the frame and having a portion bent and extending through the 30 passage and arranged to bear against the depending flange of the inner sill and to extend over the opening and over the vertical flange of the outer sill.

2. The combination of a window frame 35 having guides and having an inner and an outer sill spaced apart to form a passage; a sash arranged to enter the passage; a pivoted closing device located under the sill, said inner sill having a depending flange 40 arranged to limit the movement of the closing device in either of its two positions.

3. The combination of a window frame having guides and having an inner and an outer sill spaced apart to form a passage; a sash arranged to enter the passage; a closing device located under the inner sill and pivoted to the frame and arranged to close the opening when the sash is raised, said closing device having an inclined portion extending under the sash when the sash is raised; and means for limiting the movement of the said closing device.

GEORGE B. KOHLER.
